UNITED STATES PATENT OFFICE.

DE VER H. WARNER AND DE VER C. WARNER, OF BRIDGEPORT, CONNECTICUT, AS
SIGNORS TO THE WARNER BROTHERS COMPANY, OF BRIDGEPORT, CONNECTICUT,
A CORPORATION OF CONNECTICUT.

WOMAN'S FITTED UNDERGARMENT.

Application filed April 15, 1921. Serial No. 481,581.

To all whom it may concern:

Be it known that we, DE VER H. WARNER and DE VER C. WARNER, both citizens of the United States, and residents of Bridgeport, in the county of Fairfield and State of Connecticut, have invented new and useful Improvements in Women's Fitted Undergarments, of which the following is a description.

10 This invention relates to women's fitted undergarments.

The general object of the invention is to provide such an undergarment which shall combine the advantages of a corset and a brassière, bandeaux or camisole, offering sufficient support for the figure while at the same time eliminating the discomfort incident to the wearing of the conventional corset, particularly in hot weather.

15 Another object of our invention is to provide such a garment which may be readily laundered.

Still another object of our invention is to make suitable provision for attachment of the hose supporters.

With these and other ends in view, as will hereinafter more fully appear, our invention consists in the novel construction and arrangement of parts hereinafter described and more particularly designated in the appended claim.

Referring to the drawing, which shows one specific form of our invention and which is intended merely to illustrate and not to limit our invention:

Fig. 1 shows our improved garment in place on a figure;

Fig. 2 shows the garment laid out flat.

As shown, my garment comprises an upper portion A which is provided with shoulder straps B, B, and is suitably shaped to fit over and support the bust of the wearer, and a lower portion C adapted to compress the abdomen and buttocks by means of the section D, and the tabs E, to which the hose supporters D' and E' are attached.

The upper and lower portions A, C, are either joined at the waistband or formed in one piece. But preferably the section D to which the hose supporters D' are secured extends uninterruptedly from top to bottom of the garment and is composed of substantially non-elastic material. As herein

shown, the waistband F, which should fit the figure fairly snugly, is of elastic material and extends from the section D to the center of the back on each side of the garment. This elastic belt is gathered at its point of connection with the non-elastic material, as indicated in the drawing, so that it may give circumferentially, whereby a single garment may be used satisfactorily upon different figures.

This garment preferably fastens at the back, any suitable fastening devices, such as indicated at G, being provided for this purpose. It is obvious, however, that the garment may be fastened at the front or side without sacrificing any of the advantages of our invention.

It is apparent from the above description and from an inspection of the drawing that the garment is supported on the figure by three elements, i. e., the shoulder straps B, the waistband F and the hose supporters D', E'.

In addition to affording unusual comfort to the wearer, this garment, by means of its upper portion A, forms a sufficient support and covering for the bust, thus taking the place of the usual brassière, bandeaux or camisole, and by means of its section or pad D in conjunction with the hose supporters D', supports and suppresses the abdomen, thus taking the place of a corset. Also, when the tabs or extensions E are employed, they, in conjunction with the hose supporters E', tend to compress the buttocks and control the soft flesh thereof. These tabs or extensions may be omitted entirely or instead of passing over the buttock alone as shown in the drawing, they may pass over both the buttock and the hips or over the hips alone.

Of course, the sections D and tabs E not only serve, in conjunction with the hose supporters, to support or suppress the figure as described, but they also provide a convenient means of attachment for these hose supporters, thus fulfilling another of the common functions of the corset.

The terms and expressions which we have employed are used as terms of description and not of limitation, and we have no intention, in the use of such terms and expressions of excluding any equivalents of the features shown and described, or portions

thereof, but recognize that various modifications are possible within the scope of the invention claimed.

What we claim is:

- 5 A woman's fitted undergarment including an upper portion adapted to support and cover the bust of the wearer, a section of non-elastic material located centrally of the front of the garment and extending
- 10 from the top thereof to a point considerably below the waist of the wearer the

lower end of said section having hose supporters attached thereto and being adapted to compress the abdomen, said garment including also extensions passing over the 11 buttocks of the wearer, to each of which extensions a hose supporter is attached, an elastic waistband being interposed between said extensions and said upper portion.

D. V. H. WARNER.
DE VER C. WARNER.
